Horace Chrisman,
BY
J. Howard Bell,
ATTORNEY.

UNITED STATES PATENT OFFICE.

HORACE CHRISMAN, OF PITTSBURG, PENNSYLVANIA.

DESIGN FOR A METER-CASE.

SPECIFICATION forming part of Design No. 22,349, dated April 11, 1893.

Application filed January 3, 1893. Serial No. 457,165. Term of patent 14 years.

To all whom it may concern:

Be it known that I, HORACE CHRISMAN, a citizen of the United States, residing at Pittsburg, in the county of Allegheny and State of Pennsylvania, have invented and produced a certain new and useful Design for Meter-Cases, of which design the following is a specification.

In the accompanying drawings: Figure 1 is a side view of a meter case showing my design, and; Fig. 2, a plan or top view of the same.

The leading feature of my design is a meter case in the form of two abutting dishes or bowl shaped sections 1, 2, which meet in or near the horizontal central plane of the case. The upper section terminates at top in a central cylindrical portion. The curved body of the meter case is fluted, or provided with a

series of curved peripheral recesses or depressions 5 which extend from a short distance 20 above the middle of the case toward its ends. The walls of the flutes or recesses are inwardly curved from their ends nearest the middle of the meter case toward their opposite ends, at which they merge into and coincide with the smooth curved surfaces of the adjacent portions of the case. 25

What I claim is—

The design for a meter case substantially as shown and described. 30

In testimony whereof I have hereunto set my hand.

HORACE CHRISMAN.
